MANUALLY OPERATED TOOL

Edward N. Winslow, Shaker Heights, Ohio

Application May 12, 1933, Serial No. 670,621

2 Claims. (Cl. 280—48)

The present invention, relating as indicated to a manually operated tool, is more particularly directed to a new and improved operating means for a tool of the character of a vacuum cleaner, sweeper or other mechanism operating over various surfaces, supported on rolling or sliding supports, and actuated by means of a handle controlled by an operator. The principal object of the invention is the provision of a tool of this character which may be more conveniently, accurately and flexibly controlled by the operator than the tools of this type now in use. More precisely stated, the general object of the invention is to provide means connecting the operating handle to a wheel supported tool such as a vacuum cleaner or lawn mower, in such a manner whereby a rotational or twisting movement of the operator's hand on the handle will be so translated as to effect rotational movement of the tool about its vertical axis.

To the accomplishment of the foregoing and related ends, said invention, then, consists of the means hereinafter fully described and particularly pointed out in the claims; the annexed drawing and the following description setting forth in detail certain mechanism embodying the invention, such disclosed means constituting, however, but one of various mechanical forms in which the principle of the invention may be used.

In said annexed drawing:

Fig. 1 is a side elevation showing a vacuum cleaner embodying my present invention; Fig. 2 is a plan view of the same; Fig. 3 is another plan view illustrating the operation of the device; and Fig. 4 is a partial section through the connecting means between handle and tool, and taken on line 4—4 of Fig. 1.

Referring now to Fig. 1, I have shown a vacuum cleaner of ordinary construction consisting of a casing 1, in which is housed the motor and fan, provided with a suction nozzle 2 and supported upon wheels 3 and 4. The ordinary vacuum cleaner is provided with a handle which is pivotally secured to the cleaner to permit of relative vertical movement of the handle with respect thereto to allow operation of the cleaner with the handle held at different levels to suit the convenience of the operator and to permit of the introduction of the cleaner under such objects as day-beds, chairs and the like, in which operation the handle of course has to be somewhat lowered. In the operation of any device of this sort, that is, a vacuum cleaner, a carpet sweeper, a lawn mower, or the like, it is necessary, in order to change the direction of movement of the tool

from the surface on which it is supported, for the operator to either bodily slide the tool sideways over the floor or to walk around until the operator is in line with the desired direction of movement. The first method of changing direction is laborious while the same not only takes additional time and steps but is sometimes impossible because of the position of other objects or constructions on or in the surface being covered. The second method is of course for the operator to swing the handle laterally to one side or the other, which is satisfactory for small changes in direction or for short strokes or movements of the tool, but is not satisfactory when the tool is to be continued through a considerable distance along the new line of movement.

In my improved tool I interpose between the handle 10 and the body or casing of the tool 1 a universal joint or more properly, a Hooke's coupling or joint, illustrated particularly in Fig. 4 of the drawing. The lower end of the handle 10 is provided with an end fork 11, in which there is pivotally mounted a block 12 by means of a pin 13 serving as an axis for relative horizontal movement between handle and block. The block 12 is also pivotally mounted in a bracket 14 secured to the casing 1 and having spaced arms, between which the end of the block 12 is mounted by means of a second pin 15 disposed at substantially right angles to the plane of the pin 13. The axes of the two pivots or pins 13 and 15 do not necessarily have to intercept at exactly right angles or constitute a perfect universal joint. Furthermore, the bracket 14 is preferably mounted at a slight angle to the vertical on the casing. The operation of this joint is dependent upon the well-known theory of operation of a Hooke's joint connecting two shafts having angularly inclined axes.

In operation the tool is moved over the surface by pushing it forwardly through the handle 10 in the ordinary manner. If it is desired to turn the tool, all that is required is to axially rotate or twist the handle 10 either to the right or left, which will cause the body of the tool to turn similarly and move to the left or right. It is possible, for example, for an operator to move in the line indicated by the arrow 16 in Fig. 2 while operating the machine in a parallel line, indicated by the arrow 17 in the same figure, by a proper manipulation of the handle.

The action will be understood from an inspection of Figs. 3 and 4. If the machine is being moved in a straight line and the handle is axially rotated to the left the only way in which this rotation can occur is by a compensating change in

the direction of movement of the machine proper, which occurs through an angular movement about the two axes 13 and 15, which is directly proportioned to the rotational movement given to the handle. Up and down movements of the handle of course have no effect upon the angular relationship between handle and casing proper so that operation of the machine in the ordinary manner is still possible, with the important added 10 advantage of complete control of the direction of movement through the single handle as heretofore.

The present invention involves but few and simple parts readily interposed between the ordinary handle and tool proper while the ordinary operation is in no way interfered with. In addition, a 15 control of the tool is provided which affords greatly increased convenience in use and increased speed in operation. It is obvious that the angular motion, either vertical or horizontal, of the handle with respect to the casing may be restrained by any convenient removable means if desired in adapting the tool to any special purpose in which only one angular motion between 20 handle and tool is desired.

It will be appreciated that the present invention is not limited to the tool specifically named above, but may be advantageously employed or incorporated in portable tools operating over and 25 upon surfaces in which the tool is moved over the surface by means of a handle which is either used solely to direct the movement of the tool as in the case of motor driven articles or as the means of manual propulsion, as in the case of a 30 vacuum cleaner, or carpet sweeper. The term "portable tool" as used herein is intended to embrace tools of the type just described, in which the tool is supported upon a horizontal surface by wheels or other means and moved over the 35 surface while performing some work upon the surface thereof.

The surfaces on which such tools may be conveniently employed may be either horizontal or sloping. For example, the present invention, if 40 embodied in a lawn mower between the handle and the tool proper, will permit employment of the lawn mower on a sloping or terraced surface

in a direction parallel to the plane of intersection between a sloping and a horizontal surface which will permit the operator to walk over the horizontal surface while directing the tool in a parallel path on the sloping surface.

Other modes of applying the principle of my invention may be employed instead of the one explained, change being made as regards the means herein disclosed, provided the means stated by any of the following claims or the equivalent 10 of such stated means be employed.

I therefore particularly point out and distinctly claim as my invention:—

1. Means for directing a wheel supported surface traversing implement comprising an elongated handle member angularly inclined with respect to the surface to be traversed by said implement and freely rotatable dual pivots connecting said handle to said implement, the axis of one of said pivots extending substantially perpendicularly to the direction of motion of said implement and in a substantially horizontal plane, the axis of the other of said pivots being substantially normal to said first named axis and at an acute angle to the vertical, whereby a twisting 25 motion of said handle about its own axis rotates said implement bodily in a horizontal plane and produces a change in the direction of motion of said implement.

2. Means for manually propelling and directing 30 a wheel supported surface traversing implement comprising an elongated handle member angularly inclined with respect to the surface to be traversed by said implement, means for connecting said handle member to said implement for movement about two non-intersecting axes, one of said axes extending substantially perpendicularly to the direction of motion of said implement and in a substantially horizontal plane, the other of said axes being substantially normal to said 35 first named axis and at an acute angle to the vertical, whereby a twisting motion of said handle about its own axis in one direction or the other rotates said implement bodily in a horizontal plane and produces a corresponding change in 40 the direction of motion of said implement.

EDWARD N. WINSLOW.
